DIRECTIONAL SIGNAL

Fred Bunny, Jenkintown, Pa.

Application September 19, 1939, Serial No. 295,553

2 Claims. (Cl. 40—133)

My invention relates to a new and useful directional signal especially adapted for use on vehicles to indicate to operators of other vehicles and pedestrians the intentions of the operator of the vehicle equipped with such a signal to stop, or turn right or left.

One of the objects of this invention is to provide several coacting apertured sheets or plates of any suitable material movable relative to each other to form words indicating what action the operator of a vehicle is going to take in the manipulation of the vehicle.

Another object of this invention is to provide a number of perforated sheets in juxtaposition and constituting a signal, said sheets being shiftable lengthwise to produce a number of different indication signs.

A further object of the present invention is to form a changeable signal by the use of a number of sheets each having perforations arranged to constitute a plurality of letters of the alphabet, said sheets being movable relative to one another to produce the desired letters in proper sequence for providing the preselected signal words or signs.

With the above and other objects in view, this invention consists of the details of construction and combination of elements hereinafter set forth and then designated by the claims.

In order that those skilled in the art to which this invention appertains may understand how to make and use the same, I will describe its construction in detail, referring by numerals to the accompanying drawings forming a part hereof, in which—

Fig. 1 is a longitudinal sectional view of a lamp casing and holder for the signal sheets illustrating one way in which the latter may be used.

Fig. 2 is a cross section of Fig. 1.

Fig. 3 is a face view of the center sheet.

Fig. 4 is a similar view of the front sheet.

Fig. 5 is also a similar view of the back sheet.

Fig. 6 is a face view of the signal when all the sheets are in a neutral position to form the word "stop."

Fig. 7 is a similar view with the front or outermost sheet shifted towards the left hand end to form the word "left."

Fig. 8 is the same kind of view with rear or innermost sheet shifted towards the right hand end to form the word "right."

Figs. 9, 10 and 11 are diagrammatic views to illustrate the relative positions of the sheets in forming the signs shown in Figs. 6, 7 and 8 respectively.

In carrying out my invention as herein embodied, 15 is the intermediate or center sheet or plate having a plurality of groups 16, 17, 18, 19, 20 and 21 of horizontally and vertically arranged rectangular perforations of various lengths and said groups, for purpose of description, are separated by dotted lines, but these lines do not form any part of the invention. The perforations in group 16 are positioned in a manner to constitute elements of the letters "S" and "R"; group 17 constitutes elements of the letters "L" and "I"; group 18 comprises elements of the letters "T," "E" and "G"; group 19 are the elements of the letter "O"; group 20 includes elements of the letters "O," "F" and "H"; and group 21 constitutes elements of the letters "P" and "T."

On the outside or in front of said sheet or plate 15 is located the front sheet or plate 22 which also has a plurality of groups 23, 24, 25, 26 and 27 of horizontally and vertically arranged rectangular perforations, said groups, for purposes of illustration only are shown in the drawings as divided from one another by dotted lines. The perforations in group 23 include elements of the letters "S" and "R"; group 24, letters "T," "L" and "I"; group 25, letters "O," "E" and "G"; group 26, letters "P," "F" and "H"; and group 27, the letter "T."

On the inside or in back of the intermediate or middle sheet or plate 15 is positioned the back or rear sheet or plate 28 which, like the other sheets, has a plurality of groups 29, 30, 31, 32, 33, 34 and 35 of horizontally and vertically arranged rectangular perforations, said groups of perforations being plainly shown by the separating dotted lines used only for purposes of identifying the groups. The perforations in group 29 include elements of the letter "R"; group 30, elements of the letters "S" and "I"; group 31, elements of the letters "T," "L" and "G"; group 32, elements of the letters "T," "E" and "H"; group 33, elements of the letters "O" and "H"; group 34, elements of the letters "O," "F" and "T"; and group 35, elements of the letters "T" and "P."

45 The sheets or plates 15, 22 and 28 are mounted in any suitable manner for sidewise longitudinal movements relative to one another to selectively register the groups of perforations having related characteristics in two or more of the sheets to produce letters of different words having different sign or signal significance or directional meaning. Illustrative of one method of accomplishing the mounting and movements of the sheets is shown in Figs. 1 and 2 wherein 36 represents a lamp housing having suitable sources of

light 37, such as electric lamps, and in front of said housing are slides or tracks 38 in which the sheets or plates are mounted in the relation specified. In front of the sheets or plates may be located a panel 39 of glass or other transparent or translucent material. This panel is preferably colored or provided with a ground or frosted surface so as to be translucent whereby light rays from the source of light passing through the registered perforations of the sheets will produce a visible signal word on the panel.

The sheets 15, 22 and 28 may be moved in several different relations, for instance, the outer sheet 22 may be moved to the left while the sheets 28 and 15 remain stationary or said sheet 22 may be held stationary and the others moved in unison to produce one signal. With the sheets then in such offset or staggered relation the sheet 28 may be moved to the right while the sheets 15 and 22 remain stationary or said sheets 15 and 22 may be moved in unison to the left while the sheet 28 remains stationary to produce a different signal.

A convenient method of changing the relation of the sheets is to mount the middle one in a stationary position and make the front and rear sheets movable so the front sheet can be moved to the left from a neutral position and back as desired and the rear sheet can be moved to the right from a neutral position and back. This can be accomplished manually or automatically through the medium of mechanism including rods 40, or wires or other equivalents attached to the sheets 22 and 28 as shown in Fig. 1.

When all of sheets 22, 15 and 28 are in a neutral position as shown in Fig. 6 and illustrated diagrammatically as in Fig. 9, the groups of perforations having the characteristics of the letters "S," "T," "O" and "P" will be in alignment and from the signal word "stop." When the sheets are so positioned that the front or outer sheet 22 is to the left of the other two sheets, as shown in Figs. 7 and 10, the signal word "left" will be formed. With the sheets 15 and 22 remaining in the last mentioned relation and the rear or inner sheet in a position to the right thereof or to the right of its neutral position the signal word "right" is formed as indicated in Figs. 8 and 11.

In every instance when the signal words are formed the perforations which are not needed

to produce the desired and selected letters are blanked out by imperforate areas of some of the sheets.

From the foregoing it will be apparent that I have provided an exceedingly simple, compact and efficient directional signal having few parts wherefore the cost of production is relatively inexpensive.

Of course I do not wish to be limited to the exact details of construction herein shown and described as these may be varied within the scope of the appended claims without departing from the spirit of my invention.

Having described my invention, what I claim as new and useful is:

1. A directional signal comprising three sheets arranged one behind another, the inner or rear sheet having groups of perforations disposed to form some of the characteristics of the letters S and R; T, L and I; O, E and G; P, F and H; and T; the intermediate or middle sheet having groups of perforations disposed to form some of the characteristics of the letters S and R; L and I; T, E and G; O; O, F and H; and P and T; the front or outer sheet having groups of perforations disposed to form some of the characteristics of the letters R; S and I; T, L and G; T and E; O and H; and O, F and T; two of the sheets being movable longitudinally whereby the groups of perforations having the same characteristics may be brought into alignment, in a selected manner, to produce desired signal words.

2. A directional signal comprising three sheets arranged one behind another, the inner or rear sheet having groups of perforations disposed to form some of the characteristics of certain letters of the alphabet; the intermediate or middle sheet having groups of perforations disposed to form some of the other characteristics of certain of said letters of the alphabet; the front or outer sheet having groups of perforations disposed to form some additional characteristics of certain of said letters of the alphabet, the three sheets having sufficient perforations in common so that complete letters appear when they are brought in certain relative positions, two of the sheets being movable longitudinally whereby the groups of perforations having the same characteristics may be brought into alignment, in a selected manner, to produce desired signal words.

FRED BUNNY.
